UNITED STATES PATENT OFFICE

2,545,568

VENETIAN BLIND

Rudy Bruner, New York, N. Y.

Application November 17, 1948, Serial No. 60,431

2 Claims. (Cl. 160—178)

1

The present invention relates to Venetian blinds and more particularly to bottom rail construction and the association of the bottom rail with the tapes and cords of such devices.

An object of this invention is to provide a novel and improved bottom rail for a Venetian blind, which affords easy and secure attachment of the cords and tapes thereto.

Another object hereof is to provide a bottom rail of the character mentioned, of novel and improved construction, which is made of sheet metal or the like and which requires no screws, staples or other similar means for attachment of the tapes and cords thereto.

A further object of the present invention is to provide a novel and improved bottom rail which is simple in construction, reasonably cheap to manufacture, and efficient in carrying out the purposes for which it is designed.

Other objects and advantages will become apparent as this disclosure proceeds.

In the accompanying drawings forming part of this specification, similar characters of reference indicate corresponding parts in all the views.

Fig. 1 is a front view of the lower portion of a Venetian blind, including a bottom rail embodying the teachings of this invention.

Fig. 2 is an enlarged "exploded" perspective view showing the components of said bottom rail and the manner in which the tapes are prepared to facilitate secure attachment of such tapes to said rail upon assembly of said components. This view is fragmentary.

Fig. 3 is a fragmentary enlarged end view of the left lower portion of Fig. 1, omitting a cap which may be included to cover the end of the bottom rail.

In the drawings, the numeral 15 designates generally a Venetian blind having the bottom rail 16, the slats 17, the cords 18 and 18' and the tapes 19 and 19'. Said bottom rail 16, which preferably is of sheet material as metal having some resilient quality, is essentially an elongated tubular structure which may be composed of a channel member 20 covered by a slat 21, the longitudinal edges of which slat sit in the opposite channels 22 and 22' formed longitudinally along the side walls of said channel member 20. In the Venetian blind assembly, the bottom rail 16 may be positioned with channel 20 inverted, and of course horizontally. The slat 21 may be slightly transversely arched, so that it may be easier to "snap" fit said slat 21, into the channels 22 and 22'. A properly positioned hole 23 is provided in the wall of the bottom rail 16, for each cord; the lower end of each cord passing through the hole provided for same, and knotted as at 24 within the lower rail 16.

The assembly of the bottom rail 16 and its association with the tapes 19 and 19' in the embodiment shown, is effected by placing the channel member 20 between each pair of tapes 19 and 19', so that it be in symmetry horizontally

2

with respect to the slats 17. The holes 23 are at positions in registry with the ends of the cords 18 and 18' respectively. Said cords are pulled through these holes and their bottom ends knotted as at 24. The bottom ends of each of the tapes is preferably made with a hem 25 by a line of stitches 26, with the bend-up ply of the hem away from the lower rail 16. The hems 25 of the several tapes are set upwardly into the channel member 20, and finally the slat 21 is snapped into the channels 22 and 22', whereby the tapes at regions adjacent the hem, are secured to the assembled bottom rail 16. It is evident that said tapes cannot work loose, because the hems prevent their withdrawal, and especially so, due to the action of the edge 27 acting as a stop against the longitudinal edge of the slat 21. Further to be noted, is that the tapes are clamped into assembly.

If desired, a plug, cap or cover, plain or ornamental, indicated by the numeral 27, may be in any suitable manner secured at the ends of the bottom rail 20.

This invention is capable of numerous forms and various adaptations, and is of course adaptable to Venetian blinds having a multiplicity of tapes and cords, without departing from the essential features herein disclosed. It is therefore intended and desired that the embodiment shown herein be deemed illustrative and not restrictive and that the patent shall cover all patentable novelty herein set forth; reference being had to the following claims rather than to the specific description herein to indicate the scope of this invention.

I claim:

1. In a Venetian blind including cords and tapes, a bottom rail comprising a channel member and a cover member engagingly positioned on the channel member and forming an elongated hollow casing therewith; the bottom ends of the tapes being positioned between said members intermediate the ends of said members and clamped thereby; the bottom end of each tape having an enlargement in thickness and such enlargement is wholly positioned free within the hollow of the bottom rail.

2. In an article as defined in claim 1, wherein each mentioned enlargement is a hem positioned whereby it would be intercepted by the cover member upon a pull of the tape exterior the bottom rail in a direction away from said rail.

RUDY BRUNER.
